US0D1046654S

(12) **United States Design Patent** (10) Patent No.: **US D1,046,654 S**
(45) Date of Patent: ** Oct. 15, 2024

(54) **RULER**

(71) Applicant: **Chongchao Zhao**, Shanghai (CN)

(72) Inventor: **Chongchao Zhao**, Shanghai (CN)

(73) Assignee: **Cya Aviation Tech Ltd**

(**) Term: **15 Years**

(21) Appl. No.: **29/881,089**

(22) Filed: **Dec. 28, 2022**

(51) LOC (14) Cl. **10-04**

(52) U.S. Cl.

USPC **D10/71; D10/64**

(58) **Field of Classification Search**

USPC **D10/64, 71**

CPC **G01B 3/02; G01B 3/04; B43L 13/145**

See application file for complete search history.
